TOOL FOR CUTTING GROOVES

Application filed August 5, 1929. Serial No. 383,544.

This invention relates to an improved tool for cutting annular grooves, adapted to retain a suitable lock ring.

An object of the invention is to provide a tool for cutting grooves such, for example, as are used in connection with certain types of wrist pin bearings, adapted to receive a lock ring, the latter functioning to limit movement of the wrist pin in its bearings.

10 A further object is to provide a tool of the class described, comprising an arbor adapted to be inserted in a bearing and adapted for rotation therein, said tool being provided with groove-cutting elements and means for feeding said elements in a radial direction with respect to the axis of the arbor, to cause the cutting terminals thereof to engage the bore of the bearing and cut grooves therein.

15 A further object is to provide a tool for cutting grooves in piston bearings, comprising two cutting elements normally having their cutting terminals situated below the periphery of the arbor to permit insertion of the arbor into the bearings, and means being provided at one end of the arbor to cause the elements to be fed outwardly in a direction to cause the cutting terminals thereof to engage the bores of the bearings and cut annular grooves therein adapted to receive 20 suitable lock rings.

25 Features of the invention reside in the simplicity of the tool; in the means provided for simultaneously feeding the two cutting elements outwardly to engage the work; and in the means for alining the elements with the work.

30 Other objects of the invention will appear from the following description and accompanying drawings and will be pointed out in the annexed claims.

35 In the accompanying drawings, there has been disclosed a structure designed to carry out the various objects of the invention, but it is to be understood that the invention is not confined to the exact features shown as various changes may be made within the scope of the claims which follow.

40 In the drawings:

45 Figure 1 is a sectional elevation showing the improved tool positioned in the wrist pin

bearings of a piston with the cutting elements in retracted position;

50 Figure 2 is a view similar to Figure 1, showing the cutting elements moved outwardly to cause the terminals thereof to cut grooves in the bearings of the piston;

55 Figure 3 is a plan view of the tool removed from the bearings;

60 Figure 4 is a cross-sectional view on the line 4—4 of Figure 2, showing only the tool;

65 Figure 5 is a perspective view showing the cam member adapted to feed the elements into and out of the work;

70 Figure 6 is a detail sectional view on the line 6—6 of Figure 1; and

75 Figure 7 is a detail sectional view showing a portion of a piston bearing and one end of a wrist pin mounted therein, and a lock ring adapted to prevent longitudinal movement of the wrist pin.

80 The novel tool featured in this invention comprises an arbor 2 having a crank handle 3 suitably secured to one end thereof by means of which the arbor may be rotated, when mounted in the piston bearings as here shown. Collars 4 are demountably secured to the arbor 2 by such means as screws 5 and prevent longitudinal movement of the arbor 2 while the tool is being operated.

85 The tool is here shown as having two cutting elements 6, each provided with a cutting terminal 7 adapted to engage the bore of the wrist pin bearings and cut grooves in the surfaces thereof, when the arbor 2 is rotated.

90 The means provided for feeding the elements in an outward direction comprises a slide 8 having reduced inclined portions 9 and 11 adapted to be received in correspondingly shaped notches 12, provided on the elements 6, as best shown in Figures 4 and 5. The top and bottom walls of the notches 12 are shaped to correspond to the inclinations of the reduced portions 9 and 11, so that when the slide 8 is moved longitudinally in the guide groove 13, provided in the arbor 2, the elements 6 will be moved transversely with respect to the arbor.

95 A threaded stem 14 has one end secured to one end of the slide 8 by means of a suit-

able screw 15, best shown in Figure 6. The stem 14 is slidably mounted in an aperture 16 terminally provided in the arbor 2, and shown in Figures 1 and 2. A knurled nut or hand grip 17 is received in threaded engagement with the stem 14, as shown.

In operation, the arbor 2, which is cylindrical in form and of a diameter substantially equal to that of the bore of the wrist pin bearings, is inserted through the bearings, as shown in Figures 1 and 2. The cutting elements are then properly adjusted with respect to the outer faces of the bearings as shown in Figure 1, after which the collars 4 are moved longitudinally upon the arbor until they are brought into engagement with the outer faces of the wrist pin bearings. The collars are then secured to the arbor 2 by the screws 5, whereupon the tool is ready for cutting the grooves.

To cut the grooves, the mechanic will grasp the crank handle 3 with one hand and the knurled nut 17 with the other, it being assumed that the piston is securely held by such means as a vise. As the arbor 2 is rotated in the wrist pin bearings, the elements 6 will be fed in a direction to cause the cutting terminals 7 thereof to engage the inner surfaces of the bearings and cut annular grooves therein. This results because of the knurled nut 17 being held stationary and the threaded stem 14 rotating with the arbor, thereby causing the stem 14 and the slide 8 to be moved longitudinally with respect to the arbor, resulting in the inclined faces 18 of the reduced portions 9 and 11 feeding the elements into the work simultaneously as the arbor is being rotated. As soon as the grooves have been cut to the proper depth as shown in Figure 2, the operator will rotate the knurled nut 17 upon the threaded stem 14 in a direction to cause it to move away from the end of the arbor 2, after which the nut 17, stem 14 and slide 8 may be moved in a direction towards the right, when viewing the tool as shown in Figures 1 and 2, thereby causing the slide to be returned to the position shown in Figure 1, whereupon the collar 4 at the left hand side of the figure will be released from the arbor to permit the arbor to be removed from the bearings.

In actual operation, the collar 4, shown at the left hand side in Figures 1 and 2, may be dispensed with if desired, in which case the operator or mechanic, when starting the operation of cutting the grooves, will exert a slight pressure against the crank handle 3 in a direction towards the piston so as to hold the collar 4 adjacent to the crank handle, in engagement with the end of the bearing as shown in Figures 1 and 2. However, to prevent accidental longitudinal movement of the arbor in the wrist pin bearings, when cutting the grooves, both collars 4 are used as hereinbefore stated, thus positively retaining

the arbor in proper position with respect to the wrist pin bearings.

An important feature of this invention resides in the provision of the cutting elements 6 which are arranged so as to operate simultaneously, when the arbor is rotated, thereby causing the two grooves to be cut at the same time, resulting in the work being greatly expedited. The means for feeding the elements 6 into and out of the work is very simple in construction and comprises few parts. The elements 6 are preferably constructed from suitable rod material and are therefore cylindrical in cross-section so that they may readily be supported in the cylindrical guides 19, provided in the arbor 2, as shown in Figures 1 and 2. The slide 8 is retained in the guide groove 13 by a suitable screw 20, shown in Figures 1, 2, and 3.

Figure 7 is a detail sectional view showing a bearing 21 of a piston with a groove 22 cut in the bore thereof and a lock ring 23 mounted in the groove. The depth of the groove 22 is such that the lock ring projects into the bore of the bearing so as to engage the end of the wrist pin 24 and thus retain the wrist pin in the bearing.

We claim as our invention:

1. In a tool of the class described, the combination of an arbor having spaced apart transverse sockets therein, cutting elements movably mounted in said sockets, said arbor also having a longitudinal groove therein, a slide mounted in said groove and having inclined portions engageable with said elements, means for actuating said slide whereby the cutting elements may be moved relative to the arbor, and said longitudinal groove being open at one side to receive said slide.

2. In a tool of the class described, the combination of an arbor having spaced apart sockets therein, cutting elements movably mounted in said sockets, said arbor also having an open groove therein extending lengthwise thereof, the overall length of which is less than the overall length of the arbor, a slide mounted in said groove and having inclined portions engageable with said elements, a stem connected with said slide and projecting from one end of said arbor, and a nut received in threaded engagement with said stem whereby the stem may be actuated to move said slide for the purpose of adjusting the cutting elements, said nut being inseparably connected with said stem.

3. In a tool for cutting grooves in bearings, the combination of an arbor, spaced-apart groove-cutting elements movably mounted therein, a slide mounted for longitudinal movement in said arbor and operatively connected with said elements, means exteriorly of the arbor adapted to translate said slide whereby said elements may be moved into and out of cutting positions and means adjustably mounted on the arbor adapted to engage the

- ends of the bearing being grooved to retain the tool in adjusted position.
4. In a tool for cutting grooves in bearings, the combination of an arbor, groove-cutting elements mounted therein and movable in a direction transversely of the arbor, a slide mounted for longitudinal movement in said arbor and having inclined portions engaged with said elements, means exteriorly of the arbor adapted to translate said slide to control feeding movement of the cutting elements, and abutment collars mounted on the arbor adapted to engage the ends of the bearing to prevent longitudinal movement of the arbor when in use.
5. In a tool for cutting grooves in bearings, the combination of an arbor, groove-cutting elements mounted in said arbor and each having a notch therein, a slide mounted for longitudinal movement in said arbor and having inclined portions engaged with the notches in said elements, rotatable means exteriorly of the arbor operatively connected with said slide and whereby the latter may be actuated to control feeding movement of the cutting elements, and means mounted on the arbor adapted to engage the bearing ends to prevent longitudinal movement of the arbor when in use.
6. In a tool for cutting grooves in bearings, the combination of an arbor having spaced apart sockets therein, cutting elements movably mounted in said sockets and each having a notch in one side thereof, said arbor also having a longitudinal open groove, a flat slide movably mounted in said groove and having inclined portions engaged with the notches in said cutting elements, a threaded stem having one end connected with said slide and having its other end projecting from one end of the arbor, and means received in threaded engagement with said stem and adapted to be relatively rotated thereon, whereby said stem and slide are moved in a direction lengthwise of the arbor to cause actuation of said cutting elements, movement of said slide in one direction causing the cutting terminals of said elements to be moved outwardly beyond the periphery of said arbor, and movement of the slide in the opposite direction retracting said elements.
7. In a tool for cutting grooves in bearings, the combination of an arbor adapted to be inserted in a bearing and having spaced apart sockets therein arranged transversely thereof, a groove-cutting element movably mounted in each socket and each provided with a notch, said arbor having open groove therein extending lengthwise thereof, a flat slide movably mounted in said groove and having inclined portions engaged with the notches in said elements, a stem connected with one end of said slide and projecting from one end of the arbor, means adapted to translate said stem whereby said slide will be moved to cause

actuation of said cutting elements, means for rotating said arbor, and guide means adjustably secured to said arbor to retain it in position in the bearing.

8. In a tool for cutting grooves in bearings, the combination of an arbor adapted to be inserted in a bearing and having spaced apart sockets therein, a groove-cutting element movably mounted in each socket and each provided with a notch having inclined walls, said arbor having open groove therein extending lengthwise thereof, a slide movably mounted in said groove and having inclined surfaces engaged with the inclined walls of the notches in said elements, a stem connected with said slide and projecting from one end of the arbor, a nut received in threaded engagement with said stem, relative rotation of said nut causing said slide to move in the arbor whereby said cutting elements also are moved, means for rotating said arbor, and guide collars adjustably secured to the arbor to retain it in position in the bearing.

In witness whereof we have hereunto set our hands this 1st day of August, 1929.

CHARLES H. CLEVELAND.
